UNITED STATES PATENT OFFICE.

CHARLES SPIRO, OF NEW YORK, N. Y., ASSIGNOR TO FEDERAL ADDING MACHINE CORPORATION, OF NEW YORK, N. Y., A CORPORATION OF NEW JERSEY.

ESCAPEMENT MECHANISM.

1,388,615.

Specification of Letters Patent. Patented Aug. 23, 1921.

Application filed February 14, 1920. Serial No. 358,591.

To all whom it may concern:

Be it known that I, CHARLES SPIRO, citizen of the United States, residing at New York, in the county of New York and State 5 of New York have invented certain new and useful Improvements in Escapement Mechanism, of which the following is a specification.

This invention relates to an escapement 10 mechanism for typewriting machines and particularly to a construction adapted to be actuated by the universal bail or independently thereof by the space-bar action.

The invention has for an object to provide 15 a novel and improved construction and arrangement of parts whereby a rocking escapement yoke carries the fixed and movable dogs coöperating with a ratchet escapement wheel and is mounted to be actuated in one 20 direction by a typebar actuated universal bail, and also to be actuated independently of said bail by a space-bar connection therewith.

Another object of the invention is to 25 present a novel construction of escapement yoke having a lost-motion connection with a reciprocated type bar actuated universal bail to be operated thereby, and also provided with an operating member disposed 30 to be engaged by a space-bar connection so that the escapement may be actuated independent of the universal bail and the operated parts controlled thereby.

A further object of the invention is to 35 provide an improved construction of escapement yoke pivotally mounted upon the spring housing and carrying fixed and movable dogs coöperating with an escapement ratchet wheel, together with means by which 40 the movable dog may be withdrawn from said wheel in order to release the escapement and apply a retaining brake when desired, such parts being operated by a co-operating tabulating or other mechanism.

45 Other and further objects and advantages of the invention will be hereinafter set forth and the novel features thereof defined by the appended claims.

In the drawings,—

50 Figure 1 is a vertical section at one side of the center of the escapement mechanism; Fig. 2, a bottom plan of said mechanism; Fig. 3 a rear elevation thereof.

Fig. 4 is a detail side elevation, with parts in section, of the escapement mechanism and 55 the coöperating release and braking devices.

Fig. 5 is a detail perspective of the escape- 57 ment yoke, and

Fig. 6 is a detail of the movable dog.

Like numerals refer to like parts in the 60 several figures of the drawings.

The numeral 10 designates the frame of the machine which may be of any desired character or configuration, and supports the usual segment 11 carrying the type bars 12, 65 and also the universal bail or bar 13, adapted to be actuated by shoulders upon said type bars in the usual manner to provide a rearward reciprocation of this bail. The bail 13 may be supported in any desired manner, 70 for instance by means of the hangers 14 pivotally connected thereto at 15, and also to a bracket 16 from the rear of the segment, as shown at 17. For the purpose of restoring the bail a tension spring 18 is provided 75 at the pivot 17, and has its free end engaging the hanger 14. Extending rearwardly from the bail are arms 19 provided at their free ends with bifurcated or open sockets 20 adapted to impart motion in one direction 80 to the escapement mechanism.

This escapement mechanism comprises the usual spring devices disposed within a housing 21, which is secured in any preferred manner to the top plate 22 of the frame, and the shaft driven by said spring is provided with the gear 23 adapted to mesh with the driving rack 24 upon the carriage 25, as usual in this art. The driving shaft 26 of the escapement is provided with a brake disk 27, 90 secured thereto, and an escapement wheel 28. This wheel is of the usual toothed character, and loosely mounted upon the shaft 26 and connected thereto by means of a pawl 29 pivoted upon the wheel at 30 and held in 95 contact with a ratchet wheel 31 secured to the shaft by means of a spring 32, as shown in Fig. 2. This construction permits the reverse movement of the carriage when the escapement wheel is held.

100 The dog mechanism coöperating with the ratchet wheel is carried by a yoke member 35, which is pivotally mounted to rock upon the housing 21 in any desired manner, for instance by means of the depending lugs 105 36, from the housing carrying the pivot

screws 37, which enter pivoting ears 38, formed from the yoke 35, as shown in Figs. 3 and 5. The yoke 35 is rocked upon these pivots through the universal bail by means 5 of uprights 39 carrying lateral pins 40 which seat in the open ends 20 of the rearward arms from the bail.

The yoke 35 supports the dogs co-operating with the ratchet wheel, and for this purpose 10 is provided with a lateral frame 41 having a lug 42 at its free end, to which the fixed dog 43 is secured. This frame is also provided with a stop member 44 bent therefrom to limit the movement of the movable 15 dog 45, which is pivoted upon the yoke by a stud screw 46, and normally drawn toward said stop 44 by a tension spring 47 extending from the dog to a lug 48 upon the yoke. The movable dog 45 is mounted for both an 20 oscillatory movement toward and from the fixed dog and also a longitudinal movement upon its pivot radially toward and from the teeth of the escapement wheel. This may be accomplished in any desired manner, for 25 instance by means of the slot 49 in the movable dog 45. The yoke, when rocked in one direction by the universal bar is restored to normal position by means of a tension spring 50 secured at one end to the housing 21, and 30 at its opposite end to a lug 51 from the yoke.

The yoke is also adapted to be operated independently of the universal bail through the space bar mechanism in order that the escapement may be actuated without operation 35 of the bail and the parts controlled thereby, which results in a material saving in the wear upon the several parts and in the touch action from the space bar. For this purpose the yoke is provided with a 40 depending finger 52 having its free end 53 deflected at an angle thereto and adapted to be engaged upon its rear face by a rocker arm 54, extending from a rock-shaft 55, which is pivoted at its opposite ends 56 in 45 the frame 10 of the machine. This rock shaft 55 carries the usual forwardly extending arms 57, which are connected at the keyboard of the machine by the space bar 58, as shown in Fig. 1. For the purpose of re- 50 storing the space bar to its elevated position after depression to actuate the escapement, an arm 59 is provided thereon from which a tension spring 60 extends and is secured at 61 to the machine frame. It will be seen 55 that a depression of the space bar rocks the escapement yoke, so that the actuating pins 40 thereon move away from their seats in the universal bail, which effects an operation 60 of the escapement dogs entirely independent of the action from said bail.

When it is desired to release the escapement for tabulating or other purposes, the movable dog may be shifted upon its pivot radially of the escapement wheel by any

desired means, a preferable form of which 65 comprises the lever 62, pivoted at 63, upon the yoke and having its inner end 64 seated in a recess 65 formed on the movable dog 45, so as to provide an actuating connection therewith. This recess may be formed by a 70 projection 66 from the dog against which the end 64 of the lever bears. The opposite end 67 of the releasing lever is adapted to seat in the open or bifurcated end 68 of a push link 69. This link may be actuated 75 by any desired connections, for instance such as shown in my Patent No. 987,766, of March 28, 1911, wherein a release bail 70 mounted upon a pivot 71 is connected at 72 with a push link 69 to effect a reciprocating motion thereof. Upon the same pivot 71 a brake bail 73 is mounted and carries an upright 74 upon which a brake shoe 75 is mounted to engage the disk 27 when the escapement is released. The brake and release bails are suitably supported upon a fixed part and adapted to be actuated by contact with a reciprocating member engaging beneath the same, such as the tabulator abutment finger 76, which is slidingly 90 mounted at 77 for movement in a vertical path and provided with a shoulder 78 beneath the bails so that they are lifted thereby in the upward movement of the finger 76 and the release link and brake shoe forced 95 inward toward the co-operating members of the escapement. The tabulator finger 76 may be actuated in any preferred manner, for instance the lower end 79 thereof is pivotally connected at 80, with a rock lever 81 100 pivotally supported by the frame at 82 and restored by a spring 83. The keyboard end of the rock lever 81 has pivotally mounted thereon at 84 the push key 85 of the usual type. 105

The opposite ends of the yoke 35 are extended longitudinally as at 86, and each provided with an attached pivoting lug 87, which carries the ribbon actuating pawl 88. These pawls are pivoted to said lugs by 110 means of screws 89 and an interposed spring 90, which permits a lateral movement of the pawl arm and tooth 91, necessary in the ribbon reversing. This reversing action is not herein shown and described, as it forms the 115 subject of a separate invention. The toothed ends 91 of the ribbon feed pawls 88 engage the usual feed ratchets 92, secured to the spindles of the ribbon spools 93 mounted in the top plate 22 at the front of the machine. 120

The ribbon 95 is connected in the usual manner to the vibrator 96, adapted to be actuated from the universal bail, for instance by the connection 97 to the vibrator lever 98, 125 which has one arm 99 slidably connected to a case-shifting head 100 carried by the depending arm 101 from the universal bail.

The vibrator lever 98 may be mounted in any desired manner, for instance upon a bracket 102 mounted to case-shift upon a slide 103 carried by a fixed part 104 of the machine frame. By this construction, the vibration is controlled from the universal bail, and when this part actuates the escapement yoke, there is a unitary movement of the ribbon feed. When the yoke is actuated by the space bar connection independent of the universal bail, the ribbon vibrator is left at rest, and the frictional resistance and wear due to the shifting of these parts entirely avoided, thus producing a quick and definite 15 operation of the escapement.

In the operation of the invention, it will be seen that the rearward reciprocation of the universal bail under the action of the type bar effects a rocking of the escapement 20 yoke and the feed of the dogs relative to the ratchet wheel of the escapement. This movement causes the finger depending from the yoke to move away from the actuating arm of the space bar so that the escapement is 25 operated independent thereof. The loose connection between the bail and escapement yoke effects movement of the latter only in the rearward movement of the bail, and permits the yoke to be rocked rearwardly to 30 actuate the letter space feed independent of the universal bail, as when operated through space-bar mechanisms. The mounting of the escapement yoke to rock with the dogs carried thereby provides a construction for the 35 step feed of the carriage and also for the feed of the ribbon through pawls carried by the ends of the yoke, while the construction of the movable dog permits the complete release of the escapement through cooperating 40 mechanism, such as tabulating elements. The mounting of this yoke upon the casing for the spring drum permits the entire escapement mechanism to be carried as a unit upon the under face of the rear top plate of 45 the machine so that it may be assembled thereon and directly inserted into coöperative relation with the universal bail and space bar lever, and also the brake and release bails, which are disposed upon a fixed 50 part at the rear of the machine.

It will be seen that this invention presents an efficient and economically manufactured construction of escapement mechanism adapted to coöperate with the various actuating elements of a typewriting machine, and while the details of construction have been 55 specifically described and shown, still the invention is not confined thereto, as it is obvious that changes and alterations may be 60 made therein within the scope of the appended claims.

What I claim is:

1. In a typewriter, a carriage, a motor member therefor provided with an escape-

ment wheel, a movable member pivoted upon 65 an axis intersecting that of the wheel and carrying fixed and movable dogs coöperating with said wheel, a space bar action arranged to engage and actuate said movable member, and a universal bail having means to actuate 70 said movable member independent of the space bar action.

2. In a typewriter, a carriage, a motor member therefor provided with an escapement wheel, a depending rocking member 75 pivoted upon the casing for said motor member and carrying fixed and movable dogs coöperating with said wheel, a space bar action arranged to engage and actuate said movable member, and a reciprocating type bar actuated 80 universal bail connected to said movable member to actuate the same in one direction.

3. In a typewriter, a carriage, a motor member therefor provided with an escapement wheel, a movable member disposed parallel to and beneath said wheel and carrying fixed and movable dogs coöperating with said wheel, a space bar action arranged to engage and actuate said movable member, and a reciprocating universal bail having an arm 90 loosely connected to actuate said movable member in its rearward travel.

4. In a typewriter, a carriage, a motor member therefor provided with an escapement wheel, a movable member disposed 95 parallel to the wheel and carrying fixed and movable dogs coöperating with said wheel, a space bar action arranged to engage and actuate said movable member, and a reciprocating universal bail having rearwardly extended arms at opposite sides of the motor member adapted to engage a part of said movable member to actuate the same.

5. In a typewriter, a carriage, a motor member therefor provided with an escapement wheel, a rocking yoke disposed parallel to the wheel and provided with fixed and movable dogs coöperating therewith, risers from said yoke embracing said motor member, a universal bail, and parallel arms 100 therefrom engaging said risers to rock the yoke in one direction.

6. In a typewriter, a carriage, a horizontally disposed motor member therefor provided with an escapement wheel, a rocking 115 yoke disposed parallel to an beneath said wheel and provided with fixed and movable dogs coöperating therewith, risers from said yoke embracing said motor member, a universal bail, parallel arms therefrom engaging 120 said risers to rock the yoke, and resilient means for restoring said yoke to initial position.

7. In a typewriter, a carriage, a motor member therefor provided with an escapement wheel, a rocking yoke disposed parallel to the wheel and provided with fixed and movable dogs coöperating with said wheel,

- a universal bail, a connection therefrom arranged to rock said yoke in one direction, resilient means for restoring said yoke to initial position, a depending member from 5 said yoke, and a space bar having an actuating member to engage said depending member to operate the yoke in one direction. 13. In a typewriter, a carriage, a motor member therefor provided with an escapement wheel, a rocker provided with fixed and movable dogs coöperating with said wheel, a universal bail, a connection therefrom to actuate said rocker, a depending tooth projection from said rocker, a rock 10 shaft, a space bar carried thereby, and an upwardly extending rock arm engaging the depending projection from said rocker. 14. In a typewriter, a carriage, a motor member therefor provided with an escapement wheel, a rocker provided with fixed and movable dogs coöperating with said wheel, a universal bail, a connection therefrom to actuate said rocker, a depending tooth projection from said rocker, a rock 15 shaft, a space bar carried thereby, an upwardly extending rock arm engaging the depending projection from said rocker at the rear face thereof, an arm extending upward from said rock shaft, and a spring connected to said arm and a fixed part for restoring the space bar mechanism. 16. In a typewriter, a frame, a carriage mounted thereon, a motor member connected to drive said carriage and provided with a 20 horizontally disposed escapement wheel, a rocking escapement yoke located parallel to and beneath said wheel, fixed and movable dogs carried by said yoke to coöperate with said wheel, and a universal bail provided 25 with means to rock said yoke in one direction. 17. In a typewriter, a frame, a carriage mounted thereon, a motor member connected to drive said carriage and provided with a horizontally disposed escapement wheel, a 30 rocking escapement yoke pivoted upon the housing of said member located parallel to and beneath said wheel, fixed and movable dogs carried by said yoke to coöperate with 35 said wheel, a universal bail having means to engage said yoke above its pivot to rock the same in one direction, and a tension spring extending from said housing to the lower portion of said yoke. 18. In a typewriter, a frame, a carriage mounted thereon, a motor member connected to drive said carriage and provided with a horizontally disposed escapement wheel, a 40 rocking escapement yoke pivoted upon the housing of said member located parallel to and beneath said wheel, fixed and movable dogs carried by said yoke to coöperate with 45 said wheel, a universal bail having means to engage said yoke above its pivot to rock the same in one direction, a tension spring extending from said housing to the lower portion of said yoke, a depending finger from the forward portion of said yoke, and a space bar mechanism having a rock arm engaging the rear face of said finger. 19. In a typewriter, a frame provided with a top plate, a housing carrying an escapement unit secured to the under face of said plate, a reciprocating universal bail adapted to detachably connect with said escapement unit, and a space bar action having a member adapted to contact with an operating element of said unit. 20. In a typewriter, a frame provided with a top plate, a housing carrying an escapement unit secured to the under face of said plate, a reciprocating universal bail adapted to detachably connect with said escapement unit, a space bar action having a member adapted to contact with an operating element 5 of said unit, releasing and braking mechanisms mounted upon a fixed part and detachably connected with said unit, and means for actuating said mechanisms. 21. In a typewriter escapement mechanism having a horizontally disposed rack wheel, a pivoted yoke member located parallel to and beneath said wheel, fixed and movable dogs mounted thereon to coöperate with said wheel, risers from said yoke provided 50 with actuating connections, and a depending projection from said yoke adapted to coöperate with independent actuating connections. 22. In a typewriter escapement mechanism having a horizontally disposed rack wheel, a pivoted yoke member located parallel to and beneath said wheel, fixed and movable dogs mounted thereon to coöperate with said wheel, risers from said yoke provided 55 with actuating connections, a depending projection from said yoke adapted to coöperate with independent actuating connections, a tension spring extending from said movable dog to said yoke, and means mounted upon said yoke for shifting said movable dog radially from said wheel. 23. In a typewriter escapement mechanism having a horizontally disposed rack wheel, a pivoted yoke member located parallel to and beneath said wheel, fixed and movable dogs mounted thereon to coöperate with said wheel, risers from said yoke provided 60 with actuating connections, a depending projection from said yoke adapted to coöperate with independent actuating connections, a tension spring extending from said movable dog to said yoke, and a lever mounted upon said yoke and engaging said movable dog to shift the same laterally of said wheel. 24. In a typewriter, an escapement mechanism comprising a spring drum or housing, a rocking yoke pivoted upon a horizontal

axis and carrying a fixed dog, an escapement wheel having a vertical axis and co-operating with said dog, and a coöperating movable dog pivotally mounted upon said yoke to travel laterally and circumferentially of said wheel.

19. In a typewriter, an escapement mechanism comprising a spring drum or housing, a rocking yoke pivoted thereon and carrying a fixed dog, an escapement wheel disposed intermediate the yoke and housing and co-operating with said dog, a coöperating movable dog pivotally mounted upon the upper face of said yoke to travel laterally and circumferentially of said wheel, and means to permit the releasing of said movable dog by its movement radially from said wheel.

20. In a typewriter, an escapement mechanism comprising a spring drum or housing, a rocking yoke pivoted thereon and carrying a fixed dog, an escapement wheel co-operating with said dog, a coöperating movable dog pivotally mounted upon said yoke to travel laterally and circumferentially of said wheel, a slotted connection at the pivot of said movable dog to permit its movement radially of said wheel, a rock lever pivoted upon the yoke intermediate its ends and having one end seated upon said movable dog, and means for actuating the other end of said lever.

21. In a typewriter, the combination with a rocking escapement mechanism, of means extended therefrom for actuating a ribbon feed, a typebar actuated universal bail having an arm disposed to contact with said escapement mechanism in substantial alinement with said means, independent means from said bail extended beneath the escapement to actuate a ribbon vibrating member, and spacing means for actuating said escapement independent of the universal bail.

22. In a typewriter, an escapement yoke comprising a horizontally disposed body portion provided with means for supporting fixed and movable dogs, pivoting lugs at each side of said body, and angularly disposed uprights carried by the body above

the pivots thereof to be engaged by a bail member.

23. In a typewriter, an escapement yoke comprising a body portion provided with means for supporting fixed and movable dogs, pivoting lugs for said body, and longitudinal arms extending from the body toward opposite sides of the typewriter and adapted to receive ribbon feed pawls.

24. In a typewriter, an escapement yoke comprising a body portion provided with means for supporting fixed and movable dogs, pivoting lugs at each side of said body, uprights carried by the body above the pivots thereof to be engaged by a bail member, oppositely extending longitudinal arms from the body adapted to receive ribbon feed pawls, and connecting means at the front and rear of said body to receive tensioning devices for the movable dog and yoke respectively.

25. In a typewriter, an escapement mechanism comprising a motor provided with an escapement wheel having peripheral teeth projecting in the plane thereof, a rocking member disposed parallel with said wheel with its axis intersecting that of the wheel, fixed and movable dogs both carried by said member at one side of said axis and at opposite faces of the wheel to laterally traverse the teeth thereof, and a angular swinging actuating extension from said member at the opposite side of its axis from said dogs.

26. In a typewriter, an escapement mechanism comprising a motor provided with an escapement wheel having peripheral teeth, a rocking member disposed parallel to said wheel with its axis intersecting that of the wheel, a fixed dog carried by said member at one side of its axis, a coöperating movable dog thereon provided with an elongated aperture at its pivoted end and a releasing seat intermediate its ends, and a release lever having one end engaging said seat to effect a movement of the dog in a substantially straight path.

In testimony whereof I affix my signature. CHARLES SPIRO.
